UNITED STATES PATENT OFFICE.

JOSEPH S. JONES, OF BROOKLYN, AND SAMUEL N. MEAD, JR., OF BALDWIN, NEW YORK,
ASSIGNORS TO CHAS. CORY & SON, INCORPORATED, OF NEW YORK, N. Y., A COR-
PORATION OF NEW YORK.

TELEPHONE SYSTEM AND APPLIANCES.

Application filed October 28, 1925. Serial No. 65,352.

Our invention relates to a telephone system which is especially useful as a fire control and battle order communication system for warships, or for other purposes when conditions 5 or requirements are more or less similar.

A general object of the invention is to provide one or more main telephone lines or "group circuits" with means for connecting in each group circuit any one or more of a 10 plurality of local stations, represented in the present particular example by stationary instruments or jack boxes at the local stations, which may be identified as fire control stations, since in the present specific embodiment 15 the invention is particularly adapted for fire control communication; but the reference to such uses is not intended to have a necessarily limiting significance.

A further object is to provide, when there 20 is more than one group circuit, for connecting any two or more of these circuits, which is usually accomplished by means of group switches and a common trunk or connector circuit. Then by connecting any one or more 25 of the local stations in the respective group circuits, intercommunication may be afforded between local stations of different group circuits.

Another object is to arrange the local or 30 fire control stations for co-operation with portable instruments, usually combined receivers and transmitters, each instrument being arranged for convenient attachment to the torso of a member of the ship's personnel, such 35 as an officer or other man at a gun station, and the portable instrument has means, such as a plug, for quick and easy connection to the stationary equipment at any one of the fire control stations. Thus the officer or member of 40 the gun crew may move from one local station to another and establish communication with a commanding officer by merely inserting the plug of the portable instrument into the jack of any stationary equipment at any gun station 45 or elsewhere about the ship. Similar instruments are provided for fire control commanders at any one or more general or control stations, and means are provided at such stations for the "plugging-in" of portable instruments of such general officers, also suitable jack or other connections may be provided for a switch board or "central" attendant.

In brief, the system, as physically embodied

to carry out the above stated objects, includes 55 means for quick and certain intercommunication between an indefinite number of local stations and through any reasonable number of group circuits by use of portable instruments attached to the bodies of the personnel. 60

The invention also includes, as incidental to the attainment of the above stated objects, suitable instruments and especially suitable local station instruments or jack boxes, and suitable portable instruments such as combined transmitters and receivers suitable for body attachment, with suitable mechanism or circuit arrangements in such instruments for proper line balancing or compensation, as sufficiently pointed out in detail hereafter. 70

The characteristics and advantages of the invention are further sufficiently explained in connection with the following detail description of the accompanying drawing, which shows one representative embodiment 75 of the invention. After considering this example, skilled persons will understand that many variations may be made, and we contemplate the employment of any structures that are properly within the scope of the appended claims. 80

Fig. 1 is a diagram illustrating the system as embodied in one form and also sufficiently representing essentials of the subordinate parts or instruments desirably employed 85 therein.

Fig. 2 is a front elevation of a portable telephone instrument (combined transmitter and receiver) adapted for "wearing" and for easy connection and disconnection to a stationary 90 local instrument or jack box.

Fig. 3 is a side elevation of the same.

Fig. 1 shows the system or system circuits, and essential features of subordinate parts or instruments, in diagram, representing the invention in one form, as embodied for fire control communication on a naval ship. The description of the system and its mechanisms, and their use for the stated purpose will sufficiently explain how the system may be used 95 or adapted for practically any analogous purpose, to provide telephonic intercommunication, especially when portable or detachable instruments are to be employed. Certain circuits and mechanisms are desirably located at a control or "central station" represented by the dot-and-dash rectangle which may be identified as a "line panel" I.P. Other cir- 100 105

cuits and mechanism may be located closely adjacent or more or less remote from the line panel as desired, these items being conveniently located on another panel identified as a group panel GP. The arrangement or grouping of circuits and instruments at central stations, such as the line panel and group panel stations are, of course, variable to a great degree.

At various other points about the ship are local stations conveniently designated as fire control stations FC¹, FC², FC³, etc. To cooperate with any one of the stationary fire control instruments, portable instruments PI are provided, which are sometimes called head sets, but are more appropriately termed portable instruments, since each preferably includes a receiver in the form of connected ear phones, sufficiently represented in the diagram by the single receiver R, and a transmitter T. Each stationary instrument includes a jack J and each portable instrument includes a plug P, to co-operate with the jacks. The characteristics of these instruments will be sufficiently further described hereafter.

The system as illustrated, is arranged for two group lines represented by the positive and negative bus conductors G¹ and G² on the line panel, where polarity is properly indicated. On this panel also are the line or supply conductors L with convenient branches all similarly designated, and with polarities indicated. The group busses extend to the group panel GP located adjacent the line panel or elsewhere, and are there provided with switches S for selective connection to common or connector busses C.

At the line panel are jacks J¹, J², etc., each corresponding to one of the fire control stations with similar numeral suffix. The outside contacts 1 and 2 of these jacks are connected to conductors 3 and 4 respectively, going to the corresponding fire control station. The inner, relatively movable contacts or springs 5 and 6 are connected to the supply conductors L of opposite polarity through balancing impedances 7 and 8 of any known or suitable type. The contacts and their respective conductors are also connected to four stationary contacts 10 to co-operate with a four-pole switch 11 with obvious connections to the group busses G¹ so that the line operator can connect or disconnect the local instrument or jack box in its respective group, at will. The panel operator or any other person may plug in to the jack J¹, whether it is connected to the group busses or not. At the line panel also, is an operator's jack station OJ having slightly modified arrangement, as later described, and the operator has a portable instrument or head set OI, which may be identical with the other portable instruments, such as P¹ etc. Of course, any suitable stationary or semi-portable instru-

ment may be substituted for the use of the operator to co-operate with jack station OJ or with the jacks J¹, etc.

It is now evident that any one or more of the station instruments FC¹, etc., may be connected to the group busses G¹, and any one or more of the station instruments FC³, etc., may be connected to the group busses G²; also, that either of the group busses G¹, G² (which represent any desired plurality) may be connected together to interconnect the station instruments of the different groups, by manipulation of the switches S. In this way flexible inter-communication is obtained to any desired extent.

Any local station instrument may be cross-connected to any group line other than its own group line. For this purpose one or more patching cords or jumpers e may be provided, each of which has at each end a plug P' to co-operate with the jacks. For example, one of the plugs of the jumper may be inserted in jack J¹ of local station instrument FC¹ and the switch 11 corresponding to that instrument opened to disconnect the local station from its normal group. The other plug P' of the jumper is then inserted in any jack such as J³ of another group line, and the corresponding switch 11 closed to connect the jack to the group, such as the group busses G². In this way any one or more local stations may be connected in a group other than their normal group line, without connecting the group line busses together.

Each fire control station or local station instrument, such as FC¹, FC², etc., has a jack J, including springs or contacts 5 and 6 corresponding to similar contacts of jack J¹, J², etc., and provided with leads 18 and 19 respectively, connecting with the line wires 3 and 4. Each jack also has another contact 15 in series with a condenser 20 and line wire 4. Each jack J also has a contact 21 in fixed relation to the relatively movable contact 5 and in series with a compensating impedance 22 connected to line wire 3.

The operator's jack OJ is similar to jacks J, except that it omits any contact such as 21 for a compensating impedance which is not needed where the impedance of only a single disconnectable instrument is involved; but it also includes relatively fixed contacts 1 and 2, similar to those provided for the same purposes in jacks J¹, J², etc.

Each plug P of the portable instruments or operator's instrument P¹ and O¹, includes contacts 5^a, 6^a and 15^a to correspond with jack springs or contacts identified by the same numbers without literal suffix. Each of the portable instruments includes a transmitter T and a receiver R, previously referred to, a conductor 30 leading from plug contact 6^a to a common connection between the transmitter and receiver, a conductor 31 from plug contact 15^a to the receiver, and a conductor

32 from plug contact 5^a to the movable contact 35 of a switch controlled by a button 36 mounted on the transmitter casing convenient to the operator (Figs. 2 and 3).

- 5 The movable switch contact co-operates with relatively fixed contacts 37 and 38, one of which is connected in series with a compensating impedance 39 to the receiver, or common receiver and transmitter connection, and the other is connected by a conductor 40 to the transmitter.

It is preferred to use in the receiver for greater efficiency, an iron cored magnet or magnets. The condensers 20 connected as shown, break the conductive connection to the magnet windings and provide for their actuation by the capacitive effect of the condensers, without affecting the polarity of the fixed magnets. Whenever any portable instrument, such as PI or OI, is plugged into a jack, the main circuit is established in an obvious way. At the same time the circuit, including the series compensating impedance 22 of the local station instrument is broken, but when the plug is removed this impedance is restored to the circuit to compensate for the impedance of the portable instrument. When any portable instrument is connected, the switch 35 is normally in the position shown, to break the transmitter circuit and maintain the receiver circuit. The compensating impedance 39 is then connected or in circuit to compensate for the impedance of the disconnected transmitter. When the user of the portable set wishes to transmit, he presses button 36, establishing the transmitter circuit in an obvious way, and at the same time throwing the compensating impedance 39 out of circuit.

40 Since any part of a large number of instruments may be connected or disconnected in any group circuit, the compensating impedances, automatically inserted and removed, are of great value in properly balancing the lines.

Figs. 2 and 3 illustrate one form of portable appliance, including a breast plate 50 having an adjustable shoulder or neck strap 51 and an adjustable belt or waist strap 52.

50 The transmitter T is mounted on an upper part of the breast plate by means of a double articulated bracket 55, and is also pivoted at 56 in the upper fork of the bracket, so that it may be easily adjusted to any convenient position near the lips of the user. The transmitter conductors are carried by a cable

60 to a junction box 61, which may have a detachable cover 62 secured by a chain 63. Cables 64 lead from the junction box to the separate units 70 constituting the receiver R, 60 which is arranged as an adjustable head set, in any known or suitable way. Plug P is connected to the junction box by a cable 75. The transmitter compensating impedance 39 is usually located in the junction box. The 65 details of this portable equipment may be varied greatly, the arrangement shown being one representative example.

We claim:

1. An intercommunicating telephone system comprising a plurality of group-line busses, each with local station instruments, connector busses, and means for connecting the busses of any group line with the connector busses line supply busses, means for connecting any group line bus to the line supply busses, each of said means including balancing impedances and a plurality of distant-station connecting switches for each group-line, and means for connecting the group-lines selectively, all said items located at a main or control station, distant stations connected to said distant station connecting switches, and means enabling the connection of any distant station to any group line other than its own group line. 75

2. An intercommunicating telephone system comprising a plurality of group-line busses, each with local station instruments, connector busses, and means for connecting the busses of any group line with the connector busses line supply busses, means for connecting any group line bus to the line supply busses, each of said means including balancing impedances and a plurality of distant-station connecting switches for each group-line, and means for connecting the group-lines selectively, all said items located at a main or control station, distant stations connected to said distant station connecting switches, and portable instruments connectible to the distant and main station instruments, and means enabling any local station instrument to be cross connected to any group line other than its own group line. 95

Signed at New York city, in the county of New York and State of New York this 22nd day of October A. D. 1925.
